UNITED STATES PATENT OFFICE.

JAMES L. MARSHALL, OF ERCILDOUN, PENNSYLVANIA.

MAIL BAG.

Application filed October 21, 1922. Serial No. 595,928.

To all whom it may concern:

Be it known that I, JAMES L. MARSHALL, a citizen of the United States, residing at Ercildoun, in the county of Chester and State of Pennsylvania, have invented certain new and useful Improvements in Mail Bags, of which the following is a specification.

My invention relates to improvements in mail bags, and more particularly to an improved metal frame secured within the open end of the mail bag and insuring a secure locking of the bag without the employment of straps such as in common use.

15 A further object is to provide improvements of this character in which the metal frame not only operates as a locking device, but also holds the bag in open position to conveniently receive the mail.

20 These objects, and other advantageous ends which will be described hereinafter, I attain in the following manner, reference being had to the accompanying drawings in which—

25 Figure 1 is a fragmentary perspective view showing the mail bag in open position equipped with my improvements.

Figure 2 is a fragmentary view in longitudinal section through the mail bag illustrating the position of the frame when the bag is locked.

30 Figure 3 is a fragmentary view in section on the line 3—3 of Figure 2, and

Figure 4 is a perspective view of one end 35 of the bar 3.

35 1 represents an ordinary mail bag having the covering flap 2 at its open end. Inside the mail bag, at its open end, is located my improved locking frame which consists of four bars 3, 4, 5, and 6 respectively.

The bars 3 and 4 are connected by a hinge 7, the bars 4 and 5 are connected by a hinge 8, and the bars 5 and 6 are connected by a hinge 9. All of the bars are secured to the inner face of the bag by rivets 10, and bar 3 is provided at its free end with a lug 11 which projects through a slot 12 in bar 6.

40 When the bag is in closed position, this lug 11 also projects through a slot 17 in bar 4, and then through an opening 13 in the bag, and through an opening 14 in the flap 2.

The lug 11 is provided with an opening

15 in its free end to receive a pad-lock 16 to secure all of the parts together and firmly hold the bag in closed position.

55 The bars 4 and 6 are preferably longer than the bars 3 and 5, so that when the bag is folded into closed position, the lug 11 will be projected through the slot 17 in bar 4, at a point removed from hinge 8, and the bag will lie comparatively flat in closed position so that the frame will not materially affect the appearance of the bag.

60 While I have described my invention as taking a particular form, it will be understood that the various parts of my invention may be changed without departing from the spirit thereof, and hence I do not limit myself to the precise construction set forth, but 70 consider that I am at liberty to make such changes and alterations as fairly come within the scope of the appended claims.

65 Having thus described my invention, what I claim as new and desire to secure by Letters Patent is:

75 1. The combination with a bag, of a frame secured within the open end of the bag and comprising a set of bars hinged together, two adjacent bars of said set having free 80 ends, the free end of one bar having a perforated lug thereon, the free end of another bar having a slot therein to receive the lug, said lug also adapted to be projected through a slot in a third bar and thence 85 through the bag.

90 2. The combination with a bag, of a frame secured within the open end of the bag and comprising a set of bars hinged together, two adjacent bars of said set having free 90 ends, the free end of one bar having a perforated lug thereon, the free end of another bar having a slot therein to receive the lug, said lug also adapted to be projected through a slot in a third bar and thence 95 through the bag, and a flap on the bag having a slot therein through which said lug is adapted to be projected when the bag is in closed position.

95 In testimony whereof I have signed my name to this specification in the presence of two subscribing witnesses.

JAMES L. MARSHALL.
